Specification for Design.

Patented Dec. 20, 1921.

Application filed March 1, 1921. Serial No. 448,851. Term of patent 14 years.

To all whom it may concern:

Be it known that I, JOHN C. KOPF, a citizen of the United States, residing in the borough of Bellevue, in the county of Allegheny and State of Pennsylvania, have invented a new, original, and ornamental Design for a Lifting-Jack, of which the following is a specification, reference being had to the accompanying drawings, forming part hereof.

In said drawings:

Figure 1 is a side elevation, and Fig. 2 is a top plan view of a lifting jack embodying the design.

I claim:

The ornamental design for a lifting jack, as shown.

JOHN C. KOPF.
